INDICATOR BOARD

Cecil Ewart Whitaker, Sheffield, England, assignor to William Jessop & Sons Limited, Sheffield, England, a British company

Application February 18, 1948, Serial No. 9,272
In Great Britain February 28, 1946

4 Claims. (Cl. 116—136)

1

This invention relates to indicator boards for indicating the time progress of persons, articles and other items such as the progress of individual workpieces in a factory and of the kind in which the boards are directly operated by hand and which display variable information.

In the case, for example, of workpieces in a factory different sets of workpieces have to undergo various and probably different operations during the course of their manufacture so that it is an advantage to have some means for determining the state of progress of each set of workpieces at any given time. Such a determination has been effected by the employment of progress control charts or progress cards, which relate to one set of workpieces only. These have a disadvantage in that they do not provide a comprehensive and more or less simultaneous indication of the state of progress of all of the sets of workpieces which is readily visible to the eye.

One of the objects of the present invention is to provide an improved form of indicator board which enables a visible indication of the state of progress of a plurality of sets of workpieces which undergo various operations during the course of their manufacture readily to be obtained.

A further object is to provide an improved indicator board for indicating the time progress of items in addition to workpieces, for example, persons where a large number of personnel have to be controlled, or articles, for example, in stores.

The indicator board provided by the present invention comprises a rectangular frame carrying at a longitudinal edge thereof a longitudinally extending panel having a plurality of longitudinally spaced guides for receiving and detachably supporting item indicating slips in longitudinally disposed relationship, a plurality of longitudinal panels each mounted removably in the frame in transverse relation to one another and to the first mentioned panel and carrying time indicating legends, the removable panels presenting collectively openings formed by a series of holes in transverse rows and longitudinally extending columns, one row of holes being provided at a position corresponding to each item indicating slip, and the holes being adapted to detachably receive time indicating elements, and a cursor mounted slidably on the frame for transverse movement across the front of the removable

2

panels, and adapted to co-operate with the time indicating elements in indicating a time by which a given progress of individual items is required.

The invention is illustrated in the accompanying drawings, wherein:

Figure 1 is a front elevation of one form of indicator board in accordance with this invention and intended to be used to indicate the state of progress of the sets of workpieces in a factory.

Figure 2 is a detailed enlarged view of the construction shown in Figure 1.

Figure 3 is a section on the line 3—3 of Figure 2.

Figures 4 and 5 are sectional views on the lines 4—4 and 5—5 respectively of Figure 1.

Figure 6 is a cross sectional end view showing a slightly modified construction.

Referring firstly to the construction shown in Figures 1 to 5 of the drawings, the indicator board there-illustrated comprises a rectangular frame 10 which is intended for mounting in a vertical position upon a wall or equivalent support, the frame comprising a pair of vertical metal side members 11 connected at their top and bottom by metal channels 12 and 13 respectively.

The frame is provided additionally with a back plate 14 of corresponding rectangular configuration and secured to the channel members 12 and 13 by transversely extending Z-shaped members 15.

The frame is stiffened intermediate its upper and lower edges by means of a transversely extending stiffening structure indicated at 16 secured to the inner face of the back plate 14 and a transversely extending T sectioned stiffening member 17 secured at each end to the vertical members 11 of the frame.

Within the frame adjacent the left hand vertical member 11 thereof is a longitudinally extending rectangular panel 18 which with the board 40 in the position illustrated extends vertically, which panel is formed of sheet metal of channel section, the flanges 19 of which are bent towards one another so as to leave a space 20 between the bent edge of each flange and the outer face of the panel.

The latter is further formed a short distance inwardly from each flange with a plurality of vertically spaced forwardly extending projections 21 which form longitudinally spaced guides for supporting therebetween item indicating slips 22 con-

veniently formed of stout paper and of a length somewhat greater than the distance between the opposed edges of the flanges 18 so that the slips can be engaged detachably with the guides by bending them slightly in a direction forwardly of the panel 18 and then straightening the strips so that their ends project into the spaces 29 aforesaid and are retained therein by engagement with the adjacent edges of the flanges 18.

The projections 21 do not extend completely up to the top of the panel 18 so as to leave a space 23 for displaying a suitable legend as indicated in Figure 1.

Mounted in transverse relation to one another so as completely to fill the remainder of the space in the frame between the right hand edge of the panel 18 and the right hand vertical member 11 are a plurality of longitudinally extending panels 24 which with the board in the position indicated, are likewise disposed vertically, which panels comprise flat metal sheets reinforced along each of their longitudinal edges by channel shaped reinforcing members 25.

Conveniently one of such panels is provided for each month of the year, i. e. twelve panels in all being employed and each of the panels are formed with holes 26 arranged in grid formation, the holes being so arranged that the panels 24 collectively present transversely extending rows of holes, one row corresponding to each indicating slip 22 and longitudinally extending columns, each column, in the arrangement illustrated, corresponding to one particular day of each week in the month corresponding to each panel 24.

The upper part of each panel 24 is provided with a space 27 for displaying a legend for indicating the particular month.

The panels 24 are mounted removably within the frame by forming the base portion 28 of the upper transverse channel sectioned frame member 12 with a number of transversely spaced slots, one of which is indicated at 29 in Figure 2 which allow of the panels being withdrawn individually therethrough by a vertical movement, such an arrangement permitting of the chronological order of the panels being re-arranged as may be desired according to the time of the year or the number of the particular week days occurring during any of the months.

The holes 26 are adapted to receive detachably indicating elements conveniently in the form of wooden pegs 30 shown in Figure 4, which pegs are coloured, one colour being assigned to each particular operation to be made upon the workpieces while the actual nature or form of the workpieces may be denoted by suitable legends on the indicating slips 22.

Each of the panels 24 may further be provided above the uppermost row of holes 26 with further holes at positions corresponding one to each vertically extending column of holes for carrying detachably figures representing particular dates, i. e. the date of a particular day of the week represented by each vertical column of holes above mentioned.

Mounted for transverse movement across the front of the panels 24 is a cursor 31 in the form of a metal sheet of generally channel form in cross section as indicated in Figure 5, the cursor being mounted for slideable transverse movement in relation to the frame by providing it at its upper and lower ends with integral guide portions 32 which engage slidably with the exterior of the upper and lower frame members 12, 13 and the ad-

jacent flange of the aforesaid Z-shaped members 15.

The cursor is further provided intermediate its upper and lower ends with a transversely extending channel shaped portion 33 which embraces partially the central forwardly extending limb of the T-shaped member 17.

The sheet metal cursor 31 is formed with transversely extending rows and longitudinally extending columns of holes 34, this spacing corresponding exactly with the spacing of the holes in the panels 24 with the rows of holes 34 in alignment with the transversely extending rows of holes in the panels 24. The amount of forward projection of the pegs 30 is such that they do not interfere with the transverse sliding movement of the cursor as will be readily apparent from Figure 4.

In utilising the indicator board above described for the control of the progress of various sets of workpieces in a factory, the nature of each of a plurality of sets of workpieces is indicated on the slips 22 and pegs are inserted in certain of the holes 26 in the panels 24, the positions of the pegs being determined either by the date by which a certain and desired operation (denoted by the colour of the peg) must be completed or by the date on which it must actually be performed, and in each transverse row of holes 26 there will be a number of differently coloured pegs which are spaced transversely from one another by a distance which represents the time interval.

The cursor 31 is slidden horizontally to a position corresponding to a predetermined date, so that it is disposed in front of the panel 24 corresponding to such date, and any pegs which remain to the left hand side of the cursor at that date indicate that the operation represented by such pegs was not performed on the required day or was not ready for operative performance upon that date. In this manner the indicator board enables a ready and visible indication to be obtained of the state of progress of operations to be performed on a plurality of sets of workpieces which undergo various operations during the course of their manufacture.

At the termination of the month represented by the extreme left hand panel 24, i. e. the termination of the month of January in the arrangement illustrated, if no pegs are left in that particular panel the month indicating legend thereon may be changed if desired, particularly if less than twelve panels 24 are provided, the legend being then changed to that of the month succeeding that depicted by the extreme right hand panel.

Pegs may further be inserted within the holes 34 on the cursor to denote for example, that changes in any of the operations employed in the manufacture of the workpieces have been noted and are so shown on the indicator board.

The holes 26 in the panels 24 as well as the holes 34 in the cursor, may be replaced by projections adapted to engage detachably and support suitable indicating elements, for example, pegs having shallow shanks which slide over the ends of these projections.

In Figure 6 is depicted an indicating board of a similar size as the board depicted in Figures 1 to 5, such board being intended for mounting upon a table and in this arrangement two boards are, in fact, provided disposed back to back, and connected together by connecting elements 35 and provided with a foot 36 for mounting the boards on a table or equivalent support. In this construction each of the boards is constructed as shown in Figures 1 to 5, including the provision of

a cursor, the two cursors being, however, omitted in the drawing.

As illustrated the board has been shown with the longitudinally extending panels 18 and 24 extending in a vertical direction in Figure 1 or in a substantially vertical direction in Figure 6, the transverse direction being horizontal but obviously the board might be turned through a right angle from the position shown in Figure 1 so that the longitudinal direction is now horizontal and the transverse direction vertical.

Although the invention has been described as applied to an indicator board for indicating the progress of a plurality of sets of workpieces which undergo various operations during the course of their manufacture it will be readily appreciated that an indicator board in accordance with the invention may be employed with advantage in connection with, for example, other items, for instance, stores control and control of personnel, in which case the indicator slips, the indicator labels and the nature of the pegs will be determined by the application.

Having thus described my invention, what I claim as new and desire to secure by Letters Patent is:

1. An indicator board for indicating the time progress of persons, articles and other items, comprising a rectangular frame carrying at one of its longitudinal edges a longitudinally extending panel having a plurality of longitudinally spaced guides for receiving and supporting detachably in longitudinally disposed relationship item indicating slips, a plurality of longitudinal panels each mounted removably in said frame in transverse relation to one another and to said first mentioned panel and carrying time indicating legends, said longitudinal panels presenting collectively openings formed by a series of holes in transverse rows and longitudinally extending columns, one row being provided at a position corresponding to each item indicating slip, said holes being adapted to receive detachably time indicating elements, and a cursor mounted slidably on said frame for transverse

movement across the front of said removable panels, said cursor being adapted to co-operate with said time indicating elements in indicating a time by which a given progress of individual items is required.

2. An indicator board for indicating the time progress of persons, articles and other items as defined in claim 1, wherein the panel carrying the item indicating slips comprises a metal sheet having longitudinally spaced projections formed thereon for engaging with opposite transverse edges of the slips, said sheet having also longitudinal oppositely directed flanges at its longitudinal edges adapted to receive and engage detachably the ends of the indicating slips.

3. An indicator board for indicating the time progress of persons, articles and other items as defined in claim 1, wherein the panels carrying the time indicating elements comprise metal sheets in which the holes formed therein are arranged in grid formation.

4. An indicator board for indicating the time progress of persons, articles and other items as defined in claim 1, wherein the cursor is mounted for transverse sliding movement on longitudinally spaced transversely extending members on the frame, said cursor having holes formed therein arranged in transverse rows and longitudinally extending columns for receiving indicating elements, said rows of holes in the cursor being aligned with the rows of holes in the board.
